United States Patent Office.

DAVID M. MEFFORD, OF NORWALK, OHIO.

Letters Patent No. 106,071, dated August 2, 1870.

IMPROVEMENT IN MACHINES FOR GRINDING HAND-SAW BLADES.

The Schedule referred to in these Letters Patent and making part of the same

I, DAVID M. MEFFORD, of Norwalk, in the county of Huron and State of Ohio, have invented certain Improvements in Machines for Grinding Hand-Saws, of which the following is a specification.

The nature and object of my invention consist in presenting hand-saw blades to a grinding-surface in such position that the part of the blade from which the greatest amount of steel is to be removed will traverse the whole grinding-surface.

In the accompanying drawing making a part of this specification—

Figure 1 is a vertical longitudinal section of a machine embodying my invention.

Figure 2 is a plan of the same, viewed from the top.

A is the frame of the machine, which should be substantially constructed, to resist the vibration of the operating parts.

B and C are shafts, attached to the frame of machine by suitable boxes, in which they turn, and are supported by their respective steps b and c, the latter of which is adjustable by means of screws m m.

The metallic table K and the grindstone or other suitable grinding-wheel H, having groove L, are firmly secured to their respective shafts C and B by means of clamps and nuts.

Motion is imparted to shaft B by a belt, acting on driving-pulley D, and is communicated to shaft C by belt G, the relative motion of the shafts B and C being regulated by the difference in the sizes of pulleys E and F, shaft B having the higher motion.

It is convenient to have the saw-plates J J J J parallelograms in form on their faces, and they should be of sufficient thickness to prevent springing under the pressure necessary to secure rapid grinding.

Their length and breadth should be sufficient to receive on their faces the saw-blades I I I I, and they may be fastened to the table by bolts or screws, with their heads countersunk into and level with the face of the plate.

The plates are furnished with adjustable dogs N N, which are fitted to and slide snugly in dovetail-grooves, cut into and across the face of the plates.

The dogs should be made of steel, with sharp edges projecting toward the center of the plate, and rising above its face high enough so that, when the edges are pressed against the face and back of the blade, they grip it tightly and hold it firmly while it is being ground.

The saw-blades should rest on the plate with their faces inward toward the axis of table K.

Hand-saws should be ground on a bevel from face to back, the back being the thinner.

This result is secured by raising the outer edge of the plate J a distance sufficient to place the plate on an angle with the table K, corresponding with the bevel desired on the saw-blades.

When the plate is raised on the above-described angle with the table, and the saw-blade is placed on it, face inward, as directed, also on a line parallel with the inner edge of the plate, it will be ground on the desired bevel from face to back, and the face an even and regular thickness from heel to point; but if it is desired to secure the bevel and, at the same time, give the face of the saw a regular taper from heel to point, leave the plate in the position described above, the face of the saw inward, as before, but place the back of the blade on a line parallel with the outer edge of the plate, or any approximation of the blade from its former to the latter position will taper the saw, when ground, in exact proportion as it approaches the latter position.

The groove L, or its equivalent, which is any means of removing or wearing away the grinding-surface of stone or grinding-wheel H, is necessary in order to prevent the mere point of the heel, at the back of the blade, from being entirely destroyed, by carrying up a square corner into the stone, as it is worn away, at the point in the stone nearest its center, which is approached by any part of the blade to be ground.

The groove must be of sufficient width to allow that point on the blade first coming in contact with the grinding-surface to pass into it.

The machine is operated as follows:

The saw-blades being in position on the saw-plates, as above described, the grindstone H and table K are rotated by belts, as above described, in the direction indicated by the arrows in fig. 2.

The table K is elevated by screws m m, or any other suitable device, until the highest point of each blade is reached by the grinding-surface.

As the backs of the saws are elevated to give the proper bevel, they come in contact with the grinding-surface first, and as the steel from near the backs of the blades is removed, the lower parts of the blades are reached and ground, until the sides of the faces of the saws are finally reached and trued up.

The blades are then turned over, and their plates elevated sufficiently to give to the second side of the blades the same bevel as was given to the first.

I am aware that a disk or table, rotating with its axis parallel with and eccentric to the axis of a rotating grinding-surface, has been long known and used. This I do not claim; but

What I claim, and desire to secure by Letters Patent, is—

1. The means hereinbefore described, for pressing

saw-blades to a grinding-surface in such a position that the parts of the blades from which the greatest amount of steel is to be removed will traverse the whole grinding-surface, in combination with the revolving table K, substantially as described.

2. The combination of the grindstone H, revolving table K, and saw-plates I, having the adjustable

dogs N, when said plates are arranged to be set at or placed upon a proper angle to give the necessary bevel to the blade, substantially as described.

DAVID M. MEFFORD.
